(57) **CLAIM**

I claim the ornamental design for a particle collector lid, as shown and described.

DESCRIPTION

FIG. 1 is a perspective view of a particle collector lid according to my new design, the broken lines of the particle collector lid are for illustrative purposes only and form no part of the claimed design;

FIG. 2 is a plan view of the particle collector lid of FIG. 1; FIG. 3 is a front elevational view of the particle collector lid of FIG. 1;

FIG. 4 is a side elevational view of the particle collector lid of FIG. 1; and,

FIG. 5 is a bottom view of the particle collector lid of FIG. 1.
